Int. Cl. D8—03, 02

U.S. Cl. D8—230

FIGURE 1 is a perspective view of a piton or the like, showing my new design;

FIGURE 2 is a side elevational view;

FIGURE 3 is an end elevational view;

FIGURE 4 is a top plan view; and

FIGURE 5 is a sectional view taken on the line 5—5 of FIGURE 2.

The dominant features of the design reside in the solid line portion.

I claim:

The ornamental design for a piton or the like, substantially as shown and described.
